BINDER FOR SHOE UPPERS

John M. Pero, Randolph, and Nathan Daniels,
Malden, Mass.

Application August 28, 1942, Serial No. 456,460

1 Claim. (Cl. 36—57)

Our present invention relates to the manufacture of boots and shoes, and more particularly to shoe uppers and the binding material known as French cord, particularly elastic binding, and to the method of making said binding and applying the same, this application being a continuation-in-part of our prior and copending application Ser. No. 382,088, filed March 6, 1941.

In the manufacture of boots and shoes, it is customary to apply a binding strip around certain edge portions of the upper, or upper and lining, by stitching an edge of the binding strip, and then folding or turning the strip over the edge of the upper, and securing the opposite unstitched edge of the tape by cement.

Such binding strips, particularly when made of elastic, are extremely difficult to prepare and coat evenly with adhesive for the stitching of the unstitched edge portion; and our invention aims to improve, perfect, and simplify this particular operation and, hence, to make the shoe upper more smoothly and evenly finished with the tape, eliminating wrinkling, simplifying the applying, and insuring a better sticking operation than has heretofore been practicable.

In carrying out our invention, we have discovered that by first coating the tape, and particularly elastic tape, that a base coat which may be either of adhesive or sizing or the like, and then applying the main adhesive coating either widthwise of the strip or along the edge portion to be unstitched, but secured by the adhesive, we obtain a greatly improved result.

The tape, if elastic, is put under tension and the base coating applied widthwise and lengthwise by any suitable means, such as by a brush, roll, or the like. Thereupon, the second or principal adhesive coating is applied on top of the now base-coated tape. This second adhesive coating may be applied along the edge, as noted, or may be applied to insure a greater mass of adhesive along the unstitched edge so as to insure better sticking. If the base coat is also of an adhesive nature, rather than as a sizing, it can be of cheaper material and yet will also merge with the second adhesive strip or coating to insure better sticking along the unstitched portion of the tape.

An important advantage of this method results in the tape, particularly elastic tape, being maintained smooth and unwrinkled, and greatly facilitates both the operation of the second adhesive coat-applying, as well as the subsequent rolling or winding on reels or spools, and the unwinding of same when being applied to the

shoe upper. As the folding and applying operations are usually performed by a folding machine, having heat to soften the adhesive coating as it is folded over and applied to the upper, we prepare the base and the final coating with a differential of heat-responsive consistency.

In making the tape, we may also apply the first or base coating by means of a solvent; and the second coating by utilizing heat as the liquefying element, which will result similarly in the heated folding machine operation, softening only the second coating and not the base coating.

Preferably, the base coating will be of a consistency to afford some sticking on the actual edge part over which the strip is folded; and the second or adhesive coating may be of sufficient width to insure sufficient sticking or adhesion on the actual edge of the upper over which the strip is folded to prevent "creeping" or wrinkling.

We may also prepare the base coating of a suitable consistency relatively with the second coating, so that the first base coat will have the melting point at a higher degree than the second coating or thin coating on the outer edge. Thus, if we prepare the base coating with a melting point, for example, of 300° F., and the second or outer edge coating of 200° F., the base coating will receive the feeding devices and stitches without any objectionable result when the elastic tape is heated and applied under a temperature of approximately 165° F. to 200° F. to render the outer or thicker layer tacky and adhesive. This temperature will also serve to soften the base coat to cause it to hug and stick the edge portion, preventing "creeping," free-floating, or wrinkling as heretofore explained.

A suitable base coating to carry out the above purpose, we find, can be made from pale crepe rubber and a filler such as talc, and preferably also some coloring matter, together with a suitable solvent such as petro-benzol to liquefy the mixture and enable it to be readily applied as a base coating to the elastic binding tape, and which will have a relatively high melting point at approximately 300° F.

For the second coating, we can use, for example, pale crepe rubber, chicken wire balata, carnauba wax, ozokerite, and cumar ground up and mixed and made liquid by heat for applying to the base-coated tape, which latter mixture would have a melting point of from 165° to 200° F.

We can thus provide a French cord coated elastic binding with a base coat preferably applied while the elastic is stretched or under ten-

tion. The base coat fills the interstices in the tape when so stretched, and this base coat may be sufficiently thin to eliminate the danger of sticking to the sewing machine feeding devices and needle, and of a non-sticking sizing, and also the second layer may be thin at the stitching edge but will preferably insure the sticking of the tape widthwise throughout its entire extent, thus more firmly binding the tape over the edge of the upper on which the tape is folded.

While we find it desirable to utilize the two-coating system as above explained, applying the same under tension, we find that it is also possible to apply a single coating of adhesive across the entire width of the tape with a substantial increase of greater thickness at the outer edge than at the sewing edge.

Other features and advantages will be herein-after more fully pointed out and claimed.

Referring to the drawing illustrating preferred embodiments of our present invention:

Fig. 1 is a diagrammatic view, partly broken away, showing our double-coating invention on elastic tape;

Fig. 2 is an enlarged cross-sectional view on the line 2—2 of Fig. 1;

Fig. 3 is an enlarged cross-sectional view on the line 3—3 of Fig. 1;

Figs. 4 and 5 are diagrammatic views illustrative of the stitching, folding, and sticking operation, applying the tape to the edge portion of a shoe upper;

Fig. 6 is a cross-sectional view illustrating the base coating thinned at the stitching edge and thickened at the opposite or sticking edge, and

Fig. 7 is a cross-sectional view showing the two coats widthwise of the tape, with a second coating thinned at the stitch-receiving edge and thickened at the outer or sticking edge.

Referring to the drawing, 1 illustrates a typical elastic tape of any desired material, and 2 is a coating of adhesive applied widthwise and lengthwise on one surface of the tape 1. Preferably, this coating extends from edge-to-edge of the tape, as close as practicable to apply same so that when the tape is put under heat and pressure, the adhesive coating 2 will not flow out beyond the edge of the tape 1 and show or "bleed."

A second coating 3 is then applied along the outer edge which insures better sticking of this edge portion while still maintaining the elastic tape 1 smooth widthwise because of the first or base adhesive coating 2, as above explained.

These coatings 2 and 3 may be of different material, or of the same adhesive, any suitable rubber cement or latex being feasible for this purpose. For the first coating 2, however, we are enabled to use a cheaper adhesive than for the second coating 3, which is an important advantage in our present invention.

In the drawing we have greatly overdrawn the relative thicknesses of the base, or first, and the second, or main, adhesive coatings in order to clarify the showing. In actual practice the base coating would be merged into the face of the tape, permeating slightly the same; and the second coating would be so thin as to not show any appreciable thickness, ribs, or riblike shoulders.

With the finished tape as shown in Fig. 1

and on cross-sectional lines 3—3, here illustrated as considerably enlarged, and with the adhesive coatings shown of greater thickness for clarity than in actual practice, the tape is applied to the usual upper materials 5 and stitched approximately along the line 6 of Figs. 1 and 4 by rows of stitching 7, with the adhesive coatings outside, and thereupon the tape is bent or folded around the stitched edge, as shown in Fig. 5, and the outer edge portion 8 with the double coated surface is folded and secured to the upper materials on the opposite side to that on which the tape is first stitched, thus giving a finished appearance to the edge of the upper 5.

It is customary to utilize a folding machine with heat-applying means so as to insure the softening of the cement just before it is folded, applied, and pressed against the edge upper. This operation effectually merges the second layer 3 into the first coating 2, flowing the adhesive together and eliminating any substantial shoulder, such as shown at 9 in Fig. 3 and overdrawn.

In Fig. 6 we have illustrated the base coat 14 of greater thickness at the edge portion to be unstitched, with an adhesive coating 15 applied in substantially uniform thickness, facilitating the applying operation of the adhesive in this manner; while in Fig. 7 the base coating 16 is applied of even thickness and the adhesive coating 18 being slightly tapered at the outer or unstitched edge.

In either of the various forms, the base coating can be made of cheaper material, whether adhesive or sizing, and thus considerable expense is saved, while giving the advantages of a thin adhesive coating, particularly at the stitching edge, which will eliminate gumming and sticking of the needle and presser-foot on the sewing machine during the stitching operation.

Our improved method, giving a greater thickness of adhesive at the outer or folded edge, giving a better stickiness thereto, while insuring adhesiveness throughout the entire width of the tape, produces a better, smoother, and more easily applied article, simplifying the operation, permitting high speed in the stitching and folding, and eliminating the objection heretofore found of insufficient stickiness and any "free-floating" over the edge being folded.

We claim:

As a new article of manufacture, an elastic binding tape adapted to have one edge portion stitched to a shoe upper, with a portion thereof folded widthwise over the edge of the upper, and secured by adhesive along the opposite edge without stitching, consisting in a relatively thin base coating of adhesive extending lengthwise and widthwise of the entire strip, and a second coating of adhesive superimposed on one marginal portion only of the base coating, said base coating having a melting point of approximately 100° F. higher than that of the thicker coating, whereby a predetermined heat will cause the second coating to become tacky and adhesive without causing the base coating to become similarly adhesive.
